UNITED STATES PATENT OFFICE.

JOHN BJORKLUND, OF RAYMOND, MONTANA.

CIGAR HOLDER.

Application filed May 13, 1920. Serial No. 381,005.

To all whom it may concern:

Be it known that I, JOHN BJORKLUND, a citizen of the United States, residing at Raymond, in the county of Sheridan and State 5 of Montana, have invented certain new and useful Improvements in Cigar Holders, of which the following is a specification.

This invention relates to improvements in cigar holders and its object is to provide 10 a simple and practical device of this type that is cheap to manufacture and neat in appearance. A further object is to provide a device for holding cigars that is sanitary and economical in use. With the foregoing 15 and other objects in view the invention consists in the combination and arrangement of parts to be hereinafter fully described, pointed out in the appended claim and illustrated in the accompanying drawing which forms a 20 part of this specification and in which—

Fig. 1 is a view of my improved cigar holder in side elevation illustrating its application.

Fig. 2 is a sectional view of a slightly 25 modified form of the device.

Fig. 3 is a cross section on line 3—3 of Fig. 1, enlarged.

Like reference characters denote corresponding parts throughout the several views. 30 The reference numeral 1 denotes a tube preferably hexagonal in cross section as shown in Fig. 3. Both ends of the tube are threaded and the end 2 is curved and provided with the bulb 3 which is readily removable and easily cleaned. The bulb 3 is 35 preferably made ornamental or fancy in appearance and of a light durable material such as aluminum or the like. The opposite end of the tube is threaded interiorly to 40 receive the mouth-piece 4.

Referring now to Fig. 1 I provide the tube

1 with the hollow perforate impaling-point 5 adapted to pierce the cigar 7 and when the cigar is lighted the smoke is drawn through the mouth-piece 4, tube 1 and impaling-point 45 5 and any moisture, nicotine or the like will gravitate into the bulb 3. The tube 1 is provided also with a sliding ring 8 the tube-engaging portion of which is of hexagonal formation to conform to the periphery of 50 said tube so that little or no lateral play of the ring upon the tube is possible. The larger portion of the sliding ring engages with the cigar 7 to retain the same in fixed position, in conjunction with the impaling-point, during the smoking operation.

Referring now to Fig. 2 the tube 1 is formed with the elongated impaling-point 9, perforated, and adapted for insertion in the non-lighted end of the cigar. This form of 60 holder permits the smoker to use the entire cigar without waste of any portion thereof thus combining efficiency and economy.

What is claimed is:—

In a cigar holder, a curved tube, a bulb 65 releasably carried at one end of said tube, a mouth piece at the other end of said tube, and an elongated perforate impaling point bent at one end for engagement with the curved tube, the main portion of said impaling tube extending parallel to and being spaced away from the curved tube for insertion in one end of a cigar as sole support for the same.

In testimony that I claim the foregoing as 75 my own I have hereto affixed my signature in the presence of two subscribing witnesses.

JOHN BJORKLUND.
